DESIGN FOR A WATCHCASE TOP

Andrew Chifari, New York, N. Y.

Application March 29, 1949, Serial No. 1,700

Term of patent 3½ years

(Cl. D42—8)

To all whom it may concern:

Be it known that I, Andrew Chifari, a citizen of the United States of America, residing in New York city, county of New York, and State of New York, have invented a new, original, and ornamental Design for a Watchcase Top, of which the following is a specification, reference being had to the accompanying drawing, forming part thereof, wherein,

I claim:

The ornamental design for a watchcase top, substantially as shown.

ANDREW CHIFARI.
